DISPLAY DEVICE

Claude W. Kress, New York, N. Y.

Application May 25, 1935, Serial No. 23,441

2 Claims. (Cl. 211—69)

My present invention relates to display fixtures, more especially for exposing to the view of the customer, an assortment of slender articles, such as tools including files, auger bits, drills and the like.

It is an object of the invention to provide a rugged, compact, attractive, relatively inexpensive display fixture of the above type, by which a wide assortment of the devices are securely held, but exposed to view in association with specification plates for facility in selection.

Another object is to provide a device of the above type, which occupies a negligible amount of the effective space on a counter and is yet stable and substantially proof against being upset or disarranged.

Another object is to provide a display of the above type, which lends itself readily to change of name plates, for alteration of prices and the like.

In the accompanying drawings, in which are shown one or more of various possible embodiments of the several features of the invention,

Fig. 1 is a front view of one embodiment of the display,

Fig. 2 is a view in transverse cross-section on line 2—2 of Fig. 1,

Fig. 3 is a plan view of the display,

Fig. 4 is a perspective view of the device on a smaller scale,

Fig. 5 is a front view of another embodiment,

Fig. 6 is a view in longitudinal cross-section taken on line 6—6 of Fig. 5, and

Fig. 7 is a view in transverse cross-section on a smaller scale, taken on line 7—7 of Fig. 6.

Referring to the drawings, the embodiment of Figs. 1 to 4 comprises a display unit, illustratively for files, comprising panel blocks B of substantial thickness, each preferably keystone shaped and ordinarily of wood. Each block includes a narrow

flat bottom 10 outwardly flared or radiating sides 11 and 12, and an arcuate top surface 13 which has a multiplicity of sockets s therein, preferably radially thereof and each preferably in the order

of one inch deep. The sockets are of assorted sizes and each serves to house the shank of a corresponding file or equivalent slender tool or article, so that when the tools are in position, they radiate upwardly and outwardly from the panel

block which rises from its narrow bottom 10.

In the preferred embodiment shown, a series, illustratively three of such blocks B', B² and B³ is employed preferably all sectors of the same angularity, but stepped for progressively greater radial height and arcuate width as shown. The

largest socket holes s³ are in the largest or rear panel block B³ for lodging the largest tools, while the smallest tools are lodged in the correspondingly smaller sockets s' of the forward panel block B', the tools of intermediate size being in the sockets s² of the middle panel block B².

A common carrier bar 15, preferably of wood, may be lodged in corresponding notches 16 in the bottoms of the respective blocks and is secured thereto by screws 17 to retain the blocks in parallel and spaced relation. The carrier bar admits of being mounted on a conventional shelf bracket 18 which in this instance is attached by means of a gooseneck 19 to the ledge 20 on top of the counter 21 and into which are threaded screws 22 passing through the carrier bar 15. The forward end of the bracket 18 may be sustained by a strut comprising the conventional long screw 23 reacting against the counter and threaded into a tapped tube 24 extending downward from the bracket 18.

The device preferably has name plates 25 on the front face of the respective panels. Said name plates designate the specifications and prices of the files or other slender articles lodged in the corresponding sockets. In the particular embodiment shown, the name plates extend in front of the respective rows of sockets, so that the device as shown, affords a stock of three units each, of an assortment of twenty-one different slender articles. The name plates are preferably of metal, each of truncated sector shape, with the contacting edges 26 thereof extending radially of the respective sector panels, said various name plates affixed as by tacks 27 in radial contact with each other, to assume an arch relation with respect to each other. The name plates cover the annular arc at the outer or upper rim of each panel, so that the name plates on all of the panels are completely exposed to view from the front of the device, each set of name plates extending above the rim of the neighboring panel block in front of it.

It is, of course, understood that the device could be made with a lesser or a greater number of the panel blocks, which may be of greater or lesser angular spread and that the tops of the respective panels may be flat or along ornamental curves, although the particular arcuate arrangement described is preferred, since the various slender articles will thus radiate outwardly from above the various panel blocks, to be spaced substantially at their tops, which facilitates selective removal.

In the embodiment of Figs. 5, 6, and 7 which is

specifically shown applied to drills, although useful for any other assortment of slender articles, a single display block 30 of generally keystone shape is shown. This block which may also be 5 of wood, is of thickness of substantially the order of its width at the reduced bottom 31 thereof. The sides 32 and 33 are shown flaring outwardly in curved relation, to afford a generally sector-shaped unit with a top 34 curved on a circular 10 arc. The top of the panel block is preferably inclined upwardly from its forward face to its rear, as appears best in Figs. 5 and 6. The various sockets S are bored downward from the inclined arcuate top, to accommodate the drills or other slender articles, which are thus caused to fan outwardly radially of the sector, and also to be stepped in the successive tiers from the front to the back of the block, for feasibility of display 15 and convenience of handling. A single name plate 36 is shown affixed to the front of the panel block and includes the appropriate specifications of the units in the respective rows of sockets (in this instance illustratively five deep), all of which sockets are of size and shape appropriate to 20 the tools they are to accommodate.

In the present case, the panel block 30 is carried on a metal support which includes an angle bar 40, a standard 41 unitary therewith, with a platform 42 at the upper end thereof, upon which 30 the panel block is secured by means of screws 43 threaded into the bottom thereof. The upright 41 of the standard is shown in Fig. 6 at an angle differing slightly from 90 degrees with respect to the angle 44 of the angle bar, so that when the 35 angle bar is affixed as by screws 45 to the usual upwardly sloping counter 46, the upright 41 will be in strictly vertical position and the face of the panel block 30 also will be vertical.

In both embodiments, it is seen that the display 40 affords an especially rugged unit for an attractive and convenient display of the article, and in both embodiments, the device does not detract from

the useful space on the counter, since the bracket in each case is supported directly at the flange or rim of the counter and the panel block or blocks are elevated well above the counter.

It will thus be seen that there is herein described an article in which the several features of this invention are embodied, and which article in service attains the various objects of the invention and is well suited to meet the requirements of practical use. 10

As many changes could be made in the above construction, and many apparently widely different embodiments of this invention could be made without departing from the scope thereof, it is intended that all matter contained in the above 15 description or shown in the accompanying drawings shall be interpreted as illustrative and not in a limiting sense.

Having thus described my invention, what I claim as new and desire to secure by Letters Patent of the United States is:—

1. A display device for an assortment of slender articles, such as drills, files, bits and the like, comprising a plurality of keystone-shaped panel blocks in parallel relation, and of graduated size, 25 a common support retaining said panel blocks in fixed spaced relation, each of said panel blocks having an arcuate upper surface with sockets therein for supporting the slender tools to radiate upwardly and outwardly therefrom. 30

2. A display device for an assortment of slender articles, such as drills, files, bits and the like, comprising a series of panel blocks of graduated height, a common bar to which said blocks are affixed in spaced parallel relation, said bar countersunk in corresponding grooves in the lower ends of said panel blocks, said bar adapted to be mounted on a gooseneck supported bracket arm over a counter, each of said panel blocks having 35 sockets in the upper arcuate surface thereof for supporting the articles. 40
